UNITED STATES PATENT OFFICE.

EDWARD H. RAPER, OF MAPLETON, IOWA, AND CHARLES E. RAPER, OF SHERIDAN, WYOMING.

VENTILATING WATER-CLOSETS.

Application filed June 9, 1923. Serial No. 644,381.

To all whom it may concern:

Be it known that EDWARD H. RAPER and CHARLES E. RAPER, citizens of the United States, residing, respectively, at Mapleton, 5 in the county of Monona and State of Iowa, and Sheridan, in the county of Sheridan and State of Wyoming, have invented new and useful Improvements in Ventilating Water-Closets, of which the following is a 10 specification.

This invention relates to water closets, and more particularly to a toilet ventilating device for removing the noxious gases from the bowl while the latter is in use.

15 One of the essential features of our invention consists in the provision of means whereby foul odors are prevented from escaping into the room, and are conducted through a tube having inclined openings 20 therein, whereby they combine with a jet of water and are drawn through a siphoning trap to the waste outlet.

25 A further object of the invention resides in providing means for normally maintaining the overflow pipe closed so that the air passing through the ventilating chamber is taken entirely from the toilet bowl, and the possibility of any air escaping from the 30 overflow to the chamber when the latter is in use is eliminated.

Referring to the drawings wherein is set forth the preferred embodiment of our invention,

Figure 1 is a side elevational view of a 35 toilet bowl with our invention attached thereto, showing parts in section.

Figure 2 is a sectional view taken substantially along the line 2—2 of Figure 1.

Figure 3 is a sectional view taken substantially along the line 3—3 of Figure 1.

Figure 4 is a sectional view taken substantially along the line 4—4 of Figure 1.

Figure 5 is an enlarged detail sectional view of the spray nozzle and the ventilating 45 tube.

Figure 6 is a rear end view partly in section, showing a slightly modified form of the invention.

Referring to the drawings, wherein like 50 numerals indicate like parts in the various views, 10 denotes a water closet bowl of the ordinary construction, provided with the lip 11 and the waste pipe 12, which has an angularly bent arm 12' that conducts 55 the waste from the bowl to any suitable outlet.

The bowl 10 is formed with the usual flushing rim 13 having circumferentially spaced perforations 14, which receive the water from the flushing tank 15 through the 60 pipe 16. The pipe 16 at its upper end terminates in an offset overflow 17, which is normally closed by means of a cork plug 18, having depending spring fingers 19, extending down into the pipe, which permit the cork to raise when the overflow is 65 needed, and guides the cork back to its normal position when the overflow is cut off.

A ventilating chamber 20 preferably positioned to one side of the bowl 70 communicates with the rim 13, through the passage 21. Traversing the chamber 20, and removably supported therein, is provided a tube 22 having downwardly inclined 75 openings 23, which are arranged to be supported within the chamber 20 by means of an annular flange 24, which rests against the lugs 25 formed on the inner periphery of the chamber. A spray nozzle 26 having a depending curved nipple 27 with a central opening 28 formed therein, extends a limited distance within the tube 22, the tube being preferably curved at its upper end as at 29 to snugly receive the nipple 27 so as to insure the proper positioning of the 85 tube 22 in the casing. Obviously, the chamber 20 may communicate directly with the bowl 10 instead of through the perforations 14 in the flushing rim, so as to receive the noxious gas in said bowl. 90

The nozzle 26 is preferably secured to the chamber 20 by means of an internally threaded recess 30 formed in the upper portion of the nozzle, which is adapted to engage a correspondingly externally threaded 95 portion 31 in the chamber 20.

The supply pipe 32, which leads to the flushing tank 15 is provided with a branch pipe 33 having preferably a manually controlled valve 34 positioned adjacent the seat 190 of the bowl so as to regulate the supply to the nozzle 26.

A siphoning trap 35, as shown in Figure 4, communicates with the ventilating chamber 20 through an opening 36, and is 195 divided by the partition 37 into the compartments 38 and 39, which are connected to each other by the orifice 40 adjacent the upper end of the partition. Under the siphonic action of the trap, the contents 110 of the ventilating chamber passes through the openings 36 and 40 and deliver to the

compartment 38, from where it passes through a spillway or opening 41 in the bottom of the compartment 38 to the horizontal portion 12' of the outlet 12 and mixes with the waste from the bowl 10 before being led to the soil pipe through the opening 42. The perforations 23 terminate at the flange 24 so that the lower portion of the tube 22 is closed, thus allowing air to be conducted from the chamber 20 into the tube only from that portion of the tube above the flange 24.

In order that the air emptied into the bottom of the chamber 20 through the tube may be prevented from escaping upward, a partition 25' is arranged to extend across the interior of the chamber 20 as shown in Figure 4. The liquid in the ventilating chamber 20 and the trap 35 is prevented from freezing by reason of the removable drain plug 43, which preferably engages an opening formed in the bottom of the chamber 20.

The nozzle 26 may be provided with a removable plug 44, which will permit the admission of any suitable solution into the nozzle so as to prevent the return of sewer gases through the ventilating chamber when the toilet is not in use for a long period of time.

In order to operate the ventilating device, it will be seen that it is merely necessary to turn the handle 34, conveniently positioned adjacent the seat, which will cause a jet of water to be admitted into the nozzle 26, from where it passes through the opening 28 down the perforated tube 22, and combines with the foul air coming from the bowl through the openings 14 and passage 21 to the chamber 20, the foul air being drawn into the tube 22 through the inclined openings 23 due to the suction created by the downward movement of the water from the nozzle 26. The water and air being combined together in the chamber 20 are delivered through the openings 36 and 40 to the compartment 38, where they are led through the spillway 41 to the arm 12' of the waste outlet 12, and carried by the opening 42 to the soil pipe.

It will be noted that by reason of the closure cap 18 on the overflow 17, the only air that is permitted to enter the ventilating chamber is that which comes from the bowl 10, and that the tube 22 may be readily removed from the interior of the chamber 20 when the nozzle 26 is disengaged from the upper portion of the chamber.

The modified form of the invention shown in Figure 6 is substantially similar to that previously set forth, with the exception that the ventilating chamber 45 is positioned closer to the bowl so that the water coming from the nozzle 46 is conducted, together with the air entering the tube 47, through the opening 48 into the trap and down the passageway 49 through the opening 50, into

the waste 51, where they are carried through the orifice 52 to any suitable outlet. It will be noted that in this compact form of the invention, the communicating passages are connected by round corners so as to reduce to a minimum the resistance of the water being conducted through the chamber and trap to the outlet.

It is to be understood that the form of the invention herein disclosed is merely illustrative, and in no sense restrictive, and that such changes as fall within the purview of a mechanic may be made without departing from the spirit of the invention and the scope of the appended claims.

We claim:

1. The combination with a water closet bowl and the waste pipe of the closet, of a ventilating chamber communicating with the bowl, means for creating suction through said chamber to withdraw foul air from the bowl comprising a perforated tube mounted within the chamber, means for causing fluid to flow through said tube, and a siphoning trap connecting said chamber and the waste pipe.

2. The combination with a water closet bowl and the waste pipe of the closet, of a ventilating chamber communicating with the bowl, means for creating suction through said chamber to withdraw foul air from the bowl comprising a perforated tube within said chamber, a spray nozzle extending within said tube, and a siphoning trap communicating with said chamber and said waste pipe.

3. The combination with a water closet bowl having a perforated flushing rim and a waste outlet, of a ventilating chamber communicating with said rim, means for creating suction through said chamber to withdraw foul air from the bowl comprising a tube having inclined perforations therein, a spray nozzle extending within said tube, and a siphoning trap communicating with said chamber and said waste outlet.

4. The combination with a water closet bowl having a perforated flushing rim and a waste outlet, of a tank communicating with said rim, a ventilating chamber connected to said bowl, a tube traversing said chamber and having inclined openings therein, a spray nozzle extending into said tube for creating suction to draw foul air from said bowl into said tube, and means for carrying the foul air from the tube to the waste outlet.

5. The combination with a water closet bowl having a perforated flushing rim and a waste outlet, of a tank communicating with said rim, a ventilating chamber having a passage communicating with said rim, a tube mounted in said chamber having downwardly inclined openings therein, means for drawing foul air from said bowl through

said openings to the interior of said tube, and a siphoning trap for receiving the air from the tube and carrying it to the said waste outlet.

5 6. The combination with a water closet bowl having a perforated flushing rim and a waste outlet, of a tank communicating with said rim, a ventilating chamber having a passage with said rim, a tube mounted in 10 said chamber having downwardly inclined openings therein for conducting foul air from said bowl to the interior of said tube, a siphoning trap for receiving the air from the tube and carrying it to the waste outlet, and means mounted in said chamber for 15 forcing the air to said waste outlet.

7. The combination with a water closet bowl having a perforated flushing rim and a waste outlet, of a tank communicating with 20 said rim, a ventilating chamber communicating with said rim and adapted to receive foul air issuing from said bowl through said perforations, a tube having inclined peripheral openings supported in 25 said chamber, a spray nozzle projecting into the upper end of said tube, means for regulating the fluid supply to said nozzle, and means for conducting the air from said tube to the waste outlet.

30 8. In combination, a water closet bowl having a perforated flushing rim, a tank, a supply pipe connecting said tank to the rim and having an offset upwardly extending overflow, a ventilating chamber communicating with said rim, a tube having downwardly inclined openings within said chamber, a spray nozzle extending within said tube, means for regulating the flow of fluid to said nozzle, a siphoning trap communicating with said chamber, and means on said overflow normally preventing air from entering said chamber through the supply pipe.

40 9. The combination with a water closet

bowl having a perforated flushing rim and 45 a waste outlet, of a tank connected to said rim, a ventilating chamber communicating with said rim, a tube provided with inclined openings supported in said chamber, a spray nozzle extending within said tube, a siphoning trap, a partition in said trap having an opening adjacent the top thereof, one side 50 of said trap communicating with said chamber, and the other side with said waste outlet, and means for conducting foul air from 55 said bowl to said outlet.

10. The combination with a water closet bowl having a perforated flushing rim and a waste outlet, of a tank connected to said rim, a ventilating chamber communicating 60 with said rim, a tube provided with inclined openings supported in said chamber, a spray nozzle extending within said tube, a siphoning trap, a partition in said trap having an opening adjacent the top thereof, one 65 side of said trap communicating with said chamber, and the other side with said waste outlet, said chamber having a removable drain plug, and means for conducting foul air from said bowl to said outlet. 70

11. In combination, a water closet bowl having a perforated flushing rim, a tank, a supply pipe connecting said tank to said rim and having an upwardly overflow extension, means normally closing said overflow, a ventilating chamber communicating with said rim, a tube having inclined openings within said chamber, a spray nozzle extending into one end of said tube, means on said nozzle for permitting supplying an anti-freezing solution to said chamber, and a siphonic trap communicating with said ventilating chamber. 75 80

In testimony whereof we have hereunto set our hands.

EDWARD H. RAPER.
CHARLES E. RAPER.
